(57) **CLAIM**

I claim the ornamental design for a portable terminal holder, substantially as shown.

DESCRIPTION

FIG. 1 is a front, left isometric view of a portable terminal holder.

FIG. 2 is a front elevation view of the portable terminal holder of FIG. 1.

FIG. 3 is a rear elevation view of the portable terminal holder of FIG. 1.

FIG. 4 is a left side elevation view of the portable terminal holder of FIG. 1.

FIG. 5 is a right side elevation view of the portable terminal holder of FIG. 1.

FIG. 6 is a top plan view of the portable terminal holder of FIG. 1; and,

FIG. 7 is a bottom plan view of the portable terminal holder of FIG. 1.

1 Claim, 6 Drawing Sheets

FIG. 1

FIG. 2

FIG. 3

FIG. 4

FIG. 5

FIG. 6
